UNITED STATES PATENT OFFICE.

BENJAMIN H. ALVEY, OF LOUISVILLE, KENTUCKY.

DESIGN FOR A ROLLER-SKID.

SPECIFICATION forming part of Design No. 35,158, dated October 1, 1901.

Application filed July 18, 1901. Serial No. 68,548. Term of patent 14 years.

To all whom it may concern:

Be it known that I, BENJAMIN H. ALVEY, a citizen of the United States, and a resident of Louisville, Jefferson county, Kentucky, have 5 invented and produced a new and original Design for Roller-Skids, of which the following is a specification, reference being had to the accompanying drawings, forming part thereof, in which drawings—

10 Figure 1 is a front view of a roller-skid embracing my design, and Fig. 2 is a longitudinal section through the line 2 2 of Fig. 1.

The leading or material features of my design for roller-skids consist of a pair of side 15 bars 1 1, connected at intervals by a series of rollers 3 3, each of which rollers is formed, essentially, of two cylindrical ends 4 4 of definite width, and a concave intermediate part 5, said rollers being arranged in parallel 20 planes one above another and with their cylindrical ends 4 4 extending outward beyond the plane of the contiguous edges of the side bars and not to the plane of the other edges

thereof. Thus, considering as the front side of the design the side thereof which occupies 25 the left-hand side in Fig. 2 and which is presented in Fig. 1, there are seen between said side bars and contiguous to the inner surfaces of the same a double row of broad convex surfaces which rise above the plane of 30 the front edges of said bars and do not extend to the rear edges thereof and an intermediate single row of concave surfaces.

Having thus described the invention, I claim—

The design for a roller-skid substantially as herein shown and described.

In testimony whereof I have signed my name to this specification, in the presence of two subscribing witnesses, at the city of Washington, District of Columbia, this 8th day of June, 1901.

BENJAMIN H. ALVEY.
